UNITED STATES PATENT OFFICE.

WILSON K. LEVERING AND ERNEST D. LEVERING, OF BALTIMORE COUNTY,
MARYLAND.

SASH-WEIGHT-MOLDING APPARATUS.

Application filed August 18, 1924. Serial No. 732,747.

The manufacture of sash weights by means of sand molds, the eyes and members being formed by means of a green sand core or a metal core or chill, has been carried on 5 extensively and with varying degrees of success and speed of operation for many years. The nature of the article and the use to which it is put, permits of the use of a rather low grade of casting, but the necessity 10 for forming sand molds and forming and placing the cores, has made it impossible, on account of the necessity for employing skilled help in the production of molds, to reduce the expense and increase the speed of 15 production to correspond to the expense and speed of production of plain uncored castings produced by means of automatic molding machines and the like.

Attempts have been made to produce sash 20 weights by means of metal molds, but the difficulty incident to the construction and operation of such molds, and particularly to cooling them properly between the casting operations, have up to the present time prevented 25 the introduction of metal molds for this purpose to any considerable extent, the sand mold with the green sand core or metal chill block being the most popular and probably the speediest method of production 30 known or used up to the present time.

The object of the present invention is to provide a metal mold sometimes referred to as a chill, for the production of sash weights, which is easily and conveniently cooled, 35 avoiding burning of the mold and deformation of the weights, and which can otherwise be conveniently and economically operated.

The present device is in the preferred 40 form provided with a plurality of alternately operating sets of mold cavities, thereby permitting an intermittent operation of each set of molds with an opportunity for cooling each set of molds while the other set 45 is in operation, without interfering with the continuity of operation of the machine.

The present mold is also water-jacketed to provide for cooling. While it is understood 50 that water-jacketing of metal molds is not a new expedient, water-jacketing of the molds in the past has not been completely successful on account of the formation of steam pockets, particularly near the top of the jacket with consequent failure of the cooling 55 process and venting of these pockets has

been difficult on account of the danger incident to the possible escape of water in the vicinity of the molten metal. This difficulty has been overcome by the provision of pet cocks by which the steam can be released and 60 by the arrangement of the circulation of cooling water, so that the latter can not reach the level of the pet cocks.

The apparatus disclosed also includes improved means for operating the mold members, avoiding clogging of the parts by dirt and scale, and means for forcing the mold parts together and locking them in close contact at separated points spaced along the rear surfaces of the mold members to hold 70 the contacting surfaces in close contact and prevent the formation of fins on the castings.

In the accompanying drawing we have illustrated a metal mold or chill embodying 75 the various features of my invention in the preferred form, and also showing a slight modification of the invention.

In the drawings—

Figure 1 is a side elevation of the molding 80 machine of my invention.

Figure 2 is an end elevation of the same taken from the right in Figure 1.

Figure 3 is an elevation looking in the direction of the arrow in Figure 1 at the in-side of one of the mold sections showing the mold cavities therein.

Figure 4 is a section through two of the mold sections taken on the line 4, 4 of Figure 6 looking in the direction of the arrow. 90

Figure 5 is a plan of a sash weight made in accordance with the invention.

Figure 6 is a top plan of the machine; and

Figure 7 is an elevation corresponding to 95 Figure 3 showing a different arrangement of the mold spaces, particularly adapted to the manufacture of small size weights.

Referring to the drawings by numerals, each of which is used to indicate the same or similar parts in the different figures, the machine as shown comprises a plurality, preferably three, of co-operating mold members 1, 2 and 3 mounted on a frame 5, consisting of upright parallel side frame members 6, and means for guiding and reciprocating the mold members 2 and 3 alternately toward and into contact with and from the central mold member 1. The intermediate mold member 1 is stationary and provided on its 100 105 110

- opposite faces which are contacted by said moving members 2 and 3 with mold cavities 8 and 9, which co-operate alternately with mold cavities 10 and 11 in the opposed surfaces 5 of the moving mold members 2 and 3 in the contacting or molding positions of said respective mold members, forming enclosed molding spaces in the desired shape of the sash weights to be produced.
- 10 Referring more specifically to the details of construction and to the operative parts of said machine, the central stationary mold member 1 which extends across the machine from side to side, is provided at each end in
- 15 the form shown with horizontal flanges or ears 12 near the vertical centre of the member 1, which rest on and are secured to the frame members 5 and 6, which latter are provided in the form shown with corresponding ears or brackets 13 in which are seated cap-screws or bolts 14, which pass through the ears or flanges 12 and hold the mold member 1 rigidly in position on the frame members, spanning the space between
- 25 the said members.

In the form of the invention shown, the moving mold members 2, 3 on the opposite sides of the stationary or intermediate mold member 1, are spaced apart and connected together to form a rigid structure by means of thrust rods 16, 17, 18 and 19, which as shown are seated in and secured to said moving mold members, one to each corner of each said mold members 2 and 3. The said thrust rods, which as aforesaid serve to guide, space and connect the moving mold members, pass through corresponding slide guide bearings or openings 20, one in each corner of the stationary mold member 1 in

40 which the said rods slide freely, providing for the reciprocation of the moving mold members 2 and 3 as a single rigid structure, transversely to the contacting surfaces of the mold members alternately to and into

45 contact with and from the intermediate or stationary mold member, one said member moving toward the stationary member as the other moves away from it.

The respective mold members 1, 2 and 3 are in the form of the invention shown, provided with ears 21 at each corner for the reciprocation of the guide or thrust rods 16. Though the manner of securing the rods 16, etc. at their ends in the moving mold members is immaterial, it is noted that these rods in the form shown are threaded at each end for a distance exceeding the thickness of the respective moving mold members and the moving mold members are spaced by means of nuts 22 threaded on to said rods to the desired position on the inside, i. e., the side toward the stationary mold member, and the moving mold members are forced up against said spacing nuts 22 by means of nuts 23 on the ends of the rods 16, etc.,

turned up against the outer surfaces of the moving mold members on the respective sides remote from the stationary mold member 1.

Referring now to Figures 1 and 2, it will be noted that each of the moving mold members 2, 3 is provided with horizontal ears 25 at each end of the mold member, projecting over and resting on the side frames 6. The side frames are provided with ways 26 upon which the ears 25 rest and slide in the direction of the length of the side frames, and at right angles to the contacting surfaces of the mold sections, and these ways are provided with an upwardly projecting rib or key 27 which engages a co-operating groove or slot 28 in the corresponding ear. The ways 26 support the weight of the moving mold members 2 and 3, which are guided by the rib or lug 27, and further guided and maintained in alignment and in their relation to each other by the rods 16, 17, 18 and 19.

The moving mold members are preferably actuated by means of a rack 30 and pinion 31, and are alternately locked in molding position by means of cams 35 and 36.

To provide for the reciprocation of the mold sections by the rack and pinion referred to, the moving mold member 2 has a pinion shaft 32 extending transversely to the frame members 5 and 6 and to the direction of reciprocation, the shaft 32 being mounted in suitable bearing blocks 33 secured to the back of the mold member 2 and provided with suitable apertures or bearings for the shaft 32. The bearing blocks 33 act as followers providing bearing surfaces for the locking cams 35 and similar bearing blocks 34 on the other moving mold member 3, providing followers or bearing surfaces for the cams 36. The pinion 31 is rigidly mounted on the shaft 32 and the rack 30 which co-operates with the pinion is secured to the frame with the teeth depending to prevent the accumulation of dirt. The rack is horizontal and extends in the direction of the frame members and in the direction of reciprocation of the parts.

In moving the mold members into and out of molding position, as hereinafter described, the shaft 32 carrying the pinion 31 is rotated first in one direction and then in the other direction by means of a hand crank 37 rigidly secured to the shaft.

It is easily understood that the moving mold members 2 and 3 being rigidly connected by the rods 16, 17, 18 and 19, move simultaneously in response to the operation of the rack and pinion, and that the stationary mold member having two sets of mold cavities 8 and 9, one set on each side, which cavities co-operate with the corresponding sets of cavities 10 and 11 in the moving mold members 2 and 3, one said moving mold

member 3 being in molding position as shown in Figure 1 in close contact with the stationary mold member 1. When the other moving mold member 2 is spaced away from the stationary mold member 1 opening the molds, releasing the castings and providing for the cooling of this mold 2 and the co-operating and corresponding mold cavities 8 in the stationary mold member 1, and that 5 the stationary mold member 1 opening the molds, releasing the castings and providing for the cooling of this mold 2 and the co-operating and corresponding mold cavities 8 in the stationary mold member 1, and that 10 when pouring into the mold cavities formed between the moving mold member 3 and the stationary mold member 1 has been completed, the molds being released by operating the cams 35 and 36, rotation of the hand 15 crank 37 operating the rack and pinion serves to open the mold cavities 9, 11, releasing the castings and providing for the cooling of this section of the mold and closes the mold cavities 8, 10, moving the mold 20 member 2 into close contact with the stationary mold member 1.

An important difficulty previously encountered in the attempt to produce iron and other metal castings by means of metal 25 molds, in the absence of an elaborate locking mechanism which slows down the operation of the machine to a considerable extent, and correspondingly increases the expense of the product, is due to the inability to hold 30 the mold sections in sufficiently close contact during pouring to close the joint between the mold sections with the result that a most objectionable fin necessitating an expensive smoothing operation in cleaning the castings is formed in the plane of separation of 35 the mold sections.

The present machine includes a closing and locking device which in combination with the other details makes it possible to 40 close the respective co-operating mold sections at each operation of the machine and force them into such close contact as to practically eliminate the fin, producing perfect casting or castings which are substantially 45 perfect in this detail in every instance. The locking device referred to is illustrated in Figures 1, 2 and 6. It consists of a series of cams 35 on the shaft 39, and a series of cams 36 on the other end of the machine. 50 The cams 35 which as shown are three in number, one at each side of the machine just inside the side frame and one in the middle, are mounted on the shaft 39 at the lefthand end of the machine, as seen in 55 Figure 1, which shaft is provided with suitable bearings 40 in each side frame. The cams 35 are operated manually by means of a cam arm 41 secured to the shaft 39 at one end, and having a considerable length, so 60 that any desired tension may be applied in operating the cam lock. The cams, as shown, are substantially semi-circular, each having a hub 42 to enclose and engage the shaft, the hub being near one end of the 65 long diameter of the cam, so that the radius

of the cam as measured from the centre of the shaft to the follower block 33 increases substantially by harmonic progression as the cam is rotated from right hand position, as seen in Figure 1. When the corresponding mold reaches molding position and the mold is locked by forcing the arm 41 downward and to the right in right-handed rotation, as seen in Figure 1, the three cams on shaft 39, see Figure 2, force 70 the mold section 2 into close contact with the mold section 1, and the three cams serve to equalize the pressure, bearing at each side and in the middle, and with the assistance of the guiding members which so control the 75 moving mold sections as to bring the molds together in co-operative relation, the mold sections are placed with the cavities in exact registration and forced together, so that the contact between the two mold sections is 80 completely closed, preventing the formation of fins on the castings as aforesaid. The manner of unlocking the mold section 2 and releasing the cams 35 by rotating the shaft 39 into lefthanded rotation, and opening the 85 mold by means of rack 30 and pinion 31, dropping the castings from the mold cavities 8, 10, and permitting these portions of the mold to cool, and moving the section 3 into molding position as shown in Figure 1, is 90 obvious, as is also the manner of locking this mold in molding position by means of the cams 36 on the shaft 43 controlled by lever arm 44. The mold sections might be 95 actuated by alternate operation of the cams, 100 but the rack and pinion is much more convenient and smoother.

The method of cooling the molds by means of water jackets is also of interest and of great importance in contributing to 105 the success of the apparatus.

Figure 4 which is a cross-section illustrating the movable mold 3 and fixed mold 1 in closed or pouring position, shows the arrangement of the water-jackets. The 110 mold sections have thin external walls 46 and thin internal walls 47 surrounding the mold cavities. These walls enclose chambers or water-jackets 49 which comprise the main volume of the mold sections. Each 115 mold section is provided at the top, see particularly Figure 2, with a pet cock 50 for releasing steam to prevent the formation of steam pockets at the top of the water jackets, it being obvious that steam being 120 lighter than water, in the absence of obstructions, will be forced to the top of the jacket, where it may be released by means of the pet cocks which are closed in the regular operation of the molding machine but 125 may be opened after each pouring or each second or third pouring as the occasion seems to require, or as determined by experiment.

The cooling system further comprises an 130

outlet 51 at the top of each water jacket near the level of the top of the mold cavity, see Figure 4, and below the extreme top of the water jacket and below the pet cocks, so 5 as to keep the water level below the pet cocks and to provide for the release of the steam without releasing the water. There is also a bottom connection or inlet 52 by which water is supplied to the jackets from 10 any suitable cooling apparatus or source of cold water, not shown, the water being led from the outlet 51 to the cooler by gravity by way of a hose 53, and from the cooler to the inlet 52 by a hose 54, the hose being 15 of flexible material to provide for the motion of the moving mold members. The water entering at 54, 52 is given but a slight head by gravity or pump.

The operation and advantages of the cooling system have been outlined. The water circulation is comparatively slow and the outlet 51 prevents accumulation of water in the top of the jacket. Continuous circulation is maintained and at frequent intervals 20 the pet cocks 50 are opened to release steam tending to form steam jackets and prevent the circulation of water in contact with the upper portions of the mold which would prevent cooling and hence 25 cause burning and destruction of the mold surfaces. In this apparatus destruction of the mold by burning is absolutely prevented, the circulation of cooling water in cooling relation to the entire molding surface being 30 maintained throughout the operation.

In Figure 7 we have shown a view corresponding to Figure 3 looking at one of the mold sections from the inside showing the mold cavities. In this form of mold section we have provided an increased number 40 of mold cavities 60 of reduced size providing for the production of a comparatively large number of weights of the small sizes, which are now largely in demand, at each 45 pouring. At the top of the mold section is a depression 61 into which the iron is first poured, and a central canal or duct 62 leads from this central depression and from this canal are lateral ducts 63 leading 50 to each of the mold cavities 60, and at the outer ends of the mold cavities remote from the central duct 62, we have shown main vents 64 opening at the top of the mold section and parallel to the central duct 62, 55 and leading to this vent from each of the mold cavities 60 is a branch vent 65 whereby the gases accumulated in the mold cavities and air impounded therein are released, preventing the formation of bubbles in the 60 castings.

The operation of the molding apparatus and the functioning of the various improvements has been fully explained in connection with the description of the apparatus. 65 The moving mold sections 2 and 3 being

permanently and rigidly connected, are moved alternately into contact with the respective opposite faces of the intermediate stationary mold member 1, bringing first one set of mold cavities 8, 10 and then the 70 other set 9, 11 into closed and operative molding position, one set of cavities with the corresponding moving mold section being opened and permitted to cool, while the other is closed for the molding operation. 75

We have also fully described the cooling of the molds by means of circulation of water through the jackets, and the manner of maintaining the level of the cooling 80 water below the top of the water jacket and below the pet cocks by means of which the steam is released after every molding operation or every second or third molding operation to prevent the formation of steam 85 pockets which would impede the circulation and keep the water out of contact with the upper portions of the mold surface. By thus maintaining the level of the water below the pet cocks any escape of water in 90 the vicinity of the melted iron is prevented.

We have thus described specifically and in detail a machine embodying our invention in the preferred form and a slight modification thereof, the specific description being provided in order that the invention and the manner of using the same may be clearly understood; however, the specific terms herein are used descriptively rather than in a limiting sense, the scope of the invention being defined in the claims. 95

What we claim and desire to secure by Letters Patent is:

1. In an apparatus for molding sash weights, two mold members, means for securing said mold members together and spacing them apart, said mold members having mold cavities in their opposed faces, an intermediate mold member between said spaced mold members, said intermediate mold member having corresponding mold cavities in its opposite faces adapted to register and co-operate with the mold cavities in the spaced mold members, and means for reciprocating some of said mold members 105 to bring the faces of the spaced mold member alternately into contact with the corresponding faces of the intermediate mold member and cause the cavities in the respective spaced mold members to co-operate alternately with the corresponding cavities in the intermediate mold member providing for the alternate closing of one set 110 of mold cavities in molding position, and the simultaneous opening and cooling of the other set of mold cavities, releasing the 115 castings therefrom. 120

2. In an apparatus for molding sash weights, two mold members, means for securing said mold members together and 130

- spacing them apart, said mold members having mold cavities in their opposed faces, an intermediate mold member between said spaced mold members, said intermediate 5 mold member having corresponding mold cavities in its opposite faces adapted to register and co-operate with the mold cavities in the spaced mold members and means for moving part of said mold members, 10 causing the cavities of the spaced mold members to co-operate alternately with the cavities in the intermediate mold member.
3. In an apparatus for molding sash weights, two mold members, means securing 15 said mold members together and spacing them apart, said mold members having mold cavities in their adjacent opposed faces, a mold member intermediate of said spaced mold members, the intermediate mold mem- 20 ber having mold cavities in its opposite faces, the cavities in the said respective opposite faces being adapted to register and co-operate with the mold cavities in the respective spaced mold members, and means 25 for reciprocating the spaced mold members, bringing their opposed faces alternately into contact with the corresponding faces of the intermediate mold member, causing the cavities in the spaced mold members to 30 co-operate alternately with the corresponding cavities in the intermediate mold member.
4. In an apparatus for molding sash weights, two mold members, means securing 35 said mold members together and spacing them apart, said mold members having mold cavities in their opposed faces, a mold mem- 40 ber intermediate of said spaced mold members, the intermediate mold member having mold cavities in its opposite faces adapted to register and co-operate with the mold 45 cavities in the spaced mold members, and means for reciprocating and guiding the spaced mold members, bringing their op- 50 posed faces alternately into contact with the corresponding faces of the intermediate mold member, causing the cavities in the spaced mold members to co-operate alternately with the corresponding cavities in the 55 third mold member, and separately operable means for locking each of said spaced mold members alternately in close contact with said intermediate mold member.
5. In an apparatus for molding sash weights, two mold members, means securing 60 said mold members together and spac- 65 ing them apart, said mold members having mold cavities in their opposed faces, a mold member intermediate of said spaced mold members, the intermediate mold member having mold cavities in its opposite faces 70 adapted to register and co-operate with the mold cavities in the spaced mold members, and separately operable means for locking each of said spaced mold members alternately in close contact with said intermediate mold member, said locking means comprising a plurality of locking units spaced apart 75 and engaging said mold member at widely separated points, causing it to contact the fixed mold member uniformly throughout 80 the engaging surfaces, and means for actuating said respective sets of locking units for each said spaced mold member simultaneously.
6. In an apparatus for molding sash 85 weights, two mold members, means securing said mold members together and spacing them apart, said mold members having mold cavities in their opposed faces, a mold member intermediate of said spaced mold 90 members, the intermediate mold member having mold cavities in its opposite faces adapted to register and co-operate with the mold cavities in the spaced mold members, and means for reciprocating and guiding 95 the spaced mold members, bringing their opposed faces alternately into contact with the corresponding faces of the intermediate mold member, causing the cavities in the spaced mold members to co-operate alternately with the corresponding cavities in the third mold member, and separately operable means for locking each of said spaced mold members alternately in close contact with said intermediate mold 100 member.
7. In an apparatus for molding sash weights, two mold members, means securing 105 said mold members together and spacing them apart, said mold members having mold cavities in their opposed faces, a mold member intermediate of spaced mold members, the intermediate mold member having mold cavities in its opposite faces adapted to register and co-operate with the 110 mold cavities in the spaced mold member, and separately operable means for locking each of said spaced mold members alternately in close contact with said intermediate mold member.
8. In a molding apparatus, a stationary 115 mold member having mold cavities in its opposite surfaces, a pair of mold members, one on each side of said stationary mold member and having mold cavities in the 120 surfaces adjacent said stationary mold member adapted to co-operate with the cavities therein, means connecting the mold members of said pair together and spacing them apart, and means for reciprocating the 125

said pair of mold members simultaneously, bringing first one and then the other of said pair of mold members into contact with the stationary mold member in operative molding position while the other of said 5 pair of mold members is spaced away from the stationary mold member and permitted to cool, said means comprising a rack and pinion, the rack teeth being turned downwardly to prevent the accumulation of grit 10 and scale, and means for locking each said respective mold members of said pair in cooperative position in relation to said fixed mold member comprising a cam shaft adjacent each said mold members of said pair, 15 and cams on said shaft spaced apart and engaging widely separated points on said mold member.

9. In an apparatus for molding sash weights, two mold members, means supporting said mold members in spaced relation, said mold members having mold cavities in their opposed faces, a third mold member intermediate of said spaced mold members having mold cavities in its opposite faces, the mold cavities on the respective sides of said intermediate mold member corresponding to and being adapted to register with the opposed mold cavities in the adjacent faces of said spaced mold members, 25 part of said mold members being movably mounted, and means for guiding part of said mold members to bring the adjacent surfaces of the intermediate mold member alternately in contact with the opposed surfaces of the spaced mold members, causing the set of corresponding cavities on one side to register, forming sash weight mold spaces and simultaneously opening cavities on the opposite side, spreading the molds 30 apart, and permitting them to cool, and vice versa.

10. In an apparatus for molding sash weights, two mold members, means rigidly connecting said mold members in spaced relation, said mold members having mold cavities in their opposed faces, a third mold member between said spaced mold members having mold cavities in its opposite faces, the mold cavities on the respective sides of 45 said mold member corresponding to and being adapted to register with the opposed mold cavities in the adjacent faces of said spaced mold members, said rigid connecting means comprising guide members with co-operating guiding means on the third mold member, and means for reciprocating said rigidly connected mold members to bring the adjacent surfaces of the intermediate mold member alternately in contact with 50 the opposed surfaces of the spaced mold members, causing the set of corresponding cavities on one side to register, forming sash weight mold spaces and simultaneously opening cavities on the opposite side,

spreading the molds apart, and permitting them to cool.

11. In an apparatus for molding sash weights, two mold members, means connecting said mold members in spaced relation, said mold members having mold cavities in their opposed faces, a third mold member between said spaced mold members having mold cavities in its opposite faces, and having guiding means, the mold cavities on the respective sides of said mold member corresponding to and being adapted to register with the opposed mold cavities in the adjacent faces of said spaced mold members, means for moving part of said mold members, placing the mold members in alternate 75 positions of registration of said cavities, and means for locking said molds in the alternate positions of registration, comprising a plurality of sets of cams spaced apart and engaging widely separated points on said mold members, and means for actuating each said set of cams simultaneously.

12. In an apparatus for molding sash weights, two mold members, means supporting said mold members in spaced relation, said mold members having mold cavities in their opposed faces, a third mold member between said spaced mold members having mold cavities in its opposite faces, the mold cavities on the respective sides of said mold member corresponding to and being adapted to register with the opposed mold cavities in the adjacent faces of said spaced mold members forming sash weight mold spaces, and means for cooling said mold members comprising water-jackets surrounding said mold cavities, an outlet near the top of the mold cavities for removing water from said jacket, means for supplying water at a lower point to said water jackets, and a steam cock at the top of each of said water jackets for releasing steam and preventing steam pockets therein.

13. In a mold for sash weights, a plurality of mold members, means for guiding and moving one of said mold members toward and into contact with and from another mold member, said mold members having molding cavities which register in the positions of contact, a water jacket surrounding said molding cavities, connections thereto, providing for the circulation of water including an outlet spaced below the top of the jacket providing for maintaining the water level below the top of each jacket, and a steam cock for releasing steam from the top of the jacket above the water level.

14. In an apparatus for molding sash weights, a two-part metal mold, means for guiding and moving one of said mold members toward and into contact with and from the other mold member, said mold members having registering molding cavities in their

adjacent faces and separate clamping means for locking said mold members in close contact.

15. A two-part metal mold for sash weights, guiding means for one of said molding members, permitting it to be moved toward and into contact with and away from the other mold member and means for moving said mold member comprising a rack and pinion, the rack teeth being turned downwardly, and independent means for locking said members in close contact.

16. A sash weight molding apparatus comprising a metal mold formed in a plurality of parts, means for guiding one of said parts toward and into contact with and away from the other of said parts, co-

operating mold cavities in the contacting surfaces of said mold parts, said mold cavities being elongated in a horizontal direction 20 and placed one over the other in parallel, and having adjacent one end of said cavities a vertical passage for the admission of the molten metal, passages connecting said cavities to said vertical passage at one end, 25 an upright vent passage opposite the other end of the mold cavities, and short passages connecting each mold cavity to each said upright vent passage.

In testimony whereof we affix our signatures.

WILSON K. LEVERING.
